UNITED STATES PATENT OFFICE.

GEORGE B. SPRING, OF NEWTON, MASSACHUSETTS.

REENFORCEMENT FOR POLES.

Application filed May 22, 1926. Serial No. 111,061.

This invention relates to means for reenforcing telephone poles, telegraph poles and other similar poles.

After a wooden pole of this nature has been in use for several years it begins to show signs of weakness at the surface of the earth, such weakness being caused by the decay in the pole occasioned by the changes in the degree of moisture to which the pole is subjected at the surface of the earth.

It has heretofore been proposed to reenforce such weakened or decayed poles by setting or driving into the earth alongside of the pole one or more vertical reenforcing members which extend into the earth for a considerable distance and which also overlie the pole for a distance above the earth, said reenforcing member or members being firmly clamped to the pole. If a pole reenforced as above described is one which is considerably decayed at the surface of the earth the strain to which the pole is subjected due to its load of wires is taken largely by the reenforcing members and where the ground in which the pole is set is hard and firm there will be sufficient earth resistance against the reenforcing member so that they will firmly hold the pole in place but if the ground is sandy or soft the earth resistance afforded by the reenforcing members is not always sufficient for this purpose.

It is one of the objects of my present invention to provide a novel construction by which the earth resistance of the reenforcing members may be increased, and which when used in soft earth will provide sufficient earth resistance to the reenforcing members to ensure that the pole will be held in its proper position.

In carrying out my invention I propose to form key members of cement or other similar material which are adapted to be placed in the earth alongside of and in contact with the reenforcing members and each of which has the face that is in engagement with the reenforcing member provided with a contour complementary to that of the reenforcing member. Because of the fact that the contacting faces of the reenforcing members and the key members have complementary shapes there will be an interlocking engagement between each key member and its reenforcing member so that any lateral strain on the pole which is transmitted to the reenforcing member will be in turn transmitted to the key members. These key

members are of a shape so that they afford a greatly increased earth resistance thus making it possible to use the reenforcing members for the poles effectively even in relatively soft earth. When the key members are in place the earth resistance which they provide augments the earth resistance of the pole butt in preventing lateral swaying movement of the pole, and the earth resistance thus afforded by both the key members and the pole butt is sufficient to hold the pole upright, even in relatively soft earth.

In order to give an understanding of the invention I have illustrated in the drawings some selected embodiments thereof which will now be described after which the novel features will be pointed out in the appended claims.

Fig. 1 is a view illustrating a pole having my improved reenforcing means applied thereto;

Fig. 2 is a section on the line 2—2, Fig. 1;

Fig. 3 is a side elevation of one of the reenforcing members;

Fig. 4 is a perspective view of one of the key members;

Fig. 5 is a view showing a modified form of the key member;

Fig. 6 is a section on the line 6—6, Fig. 1.

In the drawings 1 indicates a portion of a wooden pole such as is used for telephone, telegraph and other transmission purposes, said pole being set in the earth 2. The pole is shown as reenforced by means of two reenforcing members 3 which are set into the earth alongside of the pole and which project above the surface of the earth, said reenforcing members being clamped to the pole by means of clamp members 4 all as shown in my co-pending application, Serial No. 50,319, filed August 14, 1925. The pole is shown as weakened by decay at the surface of the earth as shown at 5, this being the reason why the reinforcements 3 are used. The reenforcing members 3 may have various cross sectional shapes, those herein shown having vertical ribs 6 extending longitudinally thereof on their outer faces and also having marginal ribs 7 at their marginal edges. If the earth 2 is relatively hard and firm these ribs furnish sufficient earth resistance to ensure that the pole will be firmly held in place but if the earth 2 is soft or sandy it is sometimes desirable that added earth resistance should be provided and it is the purpose of the present invention to pro-

vide means for giving this added earth resistance.

Such added earth resistance is secured through the medium of members 8 which I term "key members" and which may conveniently be made of cement, although they may be made of any suitable material. These key members are separate and independent from the reenforcing members and overlie the outer faces thereof, and have interlocking engagement therewith. They are of a cross sectional dimension considerably larger than the reenforcing members and thus afford considerable added earth resistance. Where the reenforcing members 3 are of the shape shown in Fig. 6 each key member will be formed with a central groove 9 of a size to fit the rib 6 of the reenforcing member and other grooves 10 of a size to receive the ribs 7 of the reenforcing member.

These key members 8 may be of any desired length depending on the amount of added earth resistance which it is desired to give to the reenforcing members. In Fig. 1 the key members are of a length to extend somewhat below the lower end of the reenforcing members. In Fig. 5 the key member is shown of less vertical dimension.

Each key member will preferably be tapered somewhat from its upper end to its lower end, it being of greater cross sectional area at the upper end than at the lower end. These key members are not united or connected to the reenforcing members, but when the key members are in place they have an interlocking connection with the reenforcing members due to the fact that the contacting faces of each key member and its corresponding reenforcing member have complementary shapes. Consequently if the upper end of the pole is subjected to any lateral pressure in the direction of the arrows *a* or *b*, Fig. 2, such pressure will be transmitted to the reenforcing members 3 and from them to the key members 8 and thus to the earth. The increased size of the key members over that of the reenforcing members gives considerable added earth resistance so that the total earth resistance by which the pole is held in upright position is that afforded by the key members added to that of the pole butt.

An advantage resulting from the tapering shape of the key members is that when they are inserted the pressure thereof against the earth due to the weight thereof tends to force the key members against the reenforcing members and thus to maintain the interlocking connection between the two.

These key members may be either driven into the earth alongside of the reenforcing members or if this is not feasible the earth may be removed sufficiently to permit the key members to be set in position after

which the earth may be tamped around the key members. In any event, the weight of the key members and the tapering shape thereof serve to maintain the interlocking connection between the key members and the reenforcing members.

While I have shown herein a reenforcing member of one shape and key members of a shape to fit such reenforcing member yet it will be obvious that the invention is equally applicable to reenforcing members of other shapes, it only being essential that the face of the key member which contacts with the reenforcing member should have a shape complementary to that of the reenforcing member so that there will be the desirable interlocking connection between the key member and reenforcing member.

The key members may be made of any suitable material without departing from the invention. It is perhaps most convenient to make them of cement or concrete because in this way they can be readily cast or molded to have the proper shape.

While I have illustrated herein some selected embodiments of the invention I do not wish to be limited to the constructional features shown.

I claim:

1. A reinforcement for poles comprising a reenforcing member set into the earth alongside of the pole and clamped to the latter above the earth and a key member separable from the reenforcing member and adapted to be set into the earth alongside of the reenforcing member but independently thereof, the face of the key member which contacts with the reenforcing member having a shape complementary thereto thereby providing an interlocking connection between said members whereby the earth resistance of the key member augments that of the pole butt in resisting swaying movement of the pole.

2. A reinforcement for poles comprising a reenforcing member set into the earth alongside of the pole and clamped to the latter above the earth, and a key member independent of and separate from the reenforcing member and set into the earth alongside of the reenforcing member, the face of the key member which contacts with the reenforcing member having a shape complementary thereto thereby providing an interlocking connection between said members, said key member tapering from the top to the bottom and providing additional earth resistance to lateral swaying movement of the pole.

In testimony whereof, I have signed my name to this specification.

GEORGE B. SPRING.
